UNITED STATES PATENT OFFICE.

CHARLES O. RYBERG, OF BROCKTON, MASSACHUSETTS.

HEEL BASE FOR SHOES.

Application filed July 7, 1928. Serial No. 290,931.

This invention relates to a shoe having an attached heel and including a heel base interposed between the heel end portion of the outsole and the heel, and having a flat 5 outer face conforming to the top or inner face of the heel, which is attached to the shoe by nails or like fasteners, extending through the heel base.

The object of the invention is to provide, 10 at a minimum expense, an article of manufacture constituting a heel base of strong, durable, and practically non-distortable construction, and including an exposed body portion composed of layers of compressible 15 material, such as leather, or a leather substitute, and a reinforcing or stiffening layer of sheet metal, which permits the use of relatively cheap flexible material, such as low grade leather, or various cheap substi- 20 tutes for leather, as the material or materials of which the body portion of the base is made.

Of the accompanying drawings forming a part of this specification,—

25 Figure 1 is a top plan view of a heel base embodying the invention.

Figure 2 is a section on line 2—2 of Figure 1.

30 Figure 3 is a section on line 3—3 of Figure 1.

Figure 4 is a perspective view.

Figure 5 is a perspective view, showing the body layer and the stiffening strip hereinafter described.

25 Figure 6 is a section on line 6—6 of Figure 5.

Figures 7 and 8 are perspective views of the inner and outer rands shown by the preceding figures.

40 Figure 9 is a fragmentary sectional view, showing the heel end portions of the outer and inner soles of a shoe, the heel base shown by Figure 2, and a heel attached to the shoe by fasteners, extending through the heel 45 base,

Figure 10 is a side view, and

Figure 11 an edge view of the stiffening strip.

50 Figure 12 is a section on line 12—12 of Figure 10.

12 designates the inner sole, 13 the outer sole, and 14 the heel which, in this instance, is a rubber heel attached to the soles 12 and 13, and to a portion 15 of the upper, by the usual nails 16.

55 My improved heel base includes a lift-

shaped body portion composed of layers of material such as leather, or a leather substitute which is sufficiently compressible to permit the hereinafter described external 60 form to be imparted to said body portion by suitable forming instrumentalities. The base includes also a stiffening layer 17, of sheet metal, entirely concealed by the body portion when the base is incorporated in 65 a shoe. The layers of which the body portion is composed, are formed, assembled, coated with cement, and united under pressure, to provide at the inner side of the base, a recessed or concave inner face formed to 70 bear on the bulging or convex outer face of the heel end portion of the outsole 13, and at the outer side of the base a substantially flat face, formed to bear on the inner or top face of the heel 14.

75 The body portion of the improved heel base includes a body layer 20 of flexible compressible material, such as leather, or a leather substitute, having a curved margin 21, and a breast margin 22, the layer being heel-shaped, and its area being less than that of the completed base. Said body portion also includes an outer rand 23, and an inner rand 24, said rands being of compressible leather. The stiffening layer 17 is an oblong strip of sheet metal, extending across the body layer 20 and spaced from the breast edge 22 thereof. The stiffening layer is cemented to the body layer, and is provided at its midlength portion with downwardly projecting spurs 27, which are preferably formed by punching the strip to downwardly displace portions of the metal thereof constituting elongated spurs which are pressed into the body layer 20 and increase the stiffness of the strip. The end portions of the stiffening strip are provided with upwardly projecting spurs 26, which are preferably burs formed by punching the strip ends, and are pressed into the upper 85 rand 23, as shown by Figure 3.

90 The thicker edge portions of the rands are cemented together outside the curved margin of the body layer, and their thin edge portions overlap and are cemented to 95 portions of the sides of said layer, the thin edge portion of the outer rand 23 being cemented also to the end portions of the stiffening strip.

100 The body layer and rands are molded and 110 compressed by suitable molding instrumentalities, so that the outer side of the heel

base is provided with a dished face, conforming to the under side of the heel end of the outsole 13, and the inner side is provided with a flat face conforming to the top 5 of the heel 14. The molding pressure somewhat curves the marginal portion 21 of the body layer and the end portions of the stiffening strip, as shown by Figures 3 and 4.

It will now be seen that the stiffening 10 strip, engaged as described with the body layer 20, and the outer rand 23, maintains the molded form of the heel base and prevents deformation of the same by warping or otherwise, while it is carried in stock.

15 The stiffening strip is narrow, so that its ends are formed to project between adjacent heel attaching nails 16, the positions of which are indicated by dotted lines in Figure 1, so that the strip does not interfere 20 with the nails.

The ends of the rands 23 and 24 may be flush with the breast edge 22 of the body layer 20, sufficient surplus material being provided to permit the trimming of said 25 ends and edge by a breasting knife. The stiffening strip, although narrow, has been found to impart to the heel base such strength and resistance to deformation that the rands and body layer may be made of 30 less substantial and expensive material than would otherwise be necessary. The described heel base may be sold to shoe manufacturers as an article of manufacture.

I claim:

35 1. A heel base formed to be interposed between the convex face of the heel end of an outsole and the top face of a heel, said base comprising a body layer having a

curved margin and a breast margin imparting a heel shape to the layer, an outer and 40 an inner rand, the thicker edge portions of the rands being cemented together outside the curved margin of the body layer, while their thin edge portions overlap and are cemented to portions of the sides of said layer, 45 the body layer and rands being molded and compressed, so that the outer side of the heel base is provided with a dished face, conforming to an outsole, and the inner side with a flat face conforming to a heel top, 50 and a sheet metal stiffening strip extending across the body layer and spaced from the breast edge thereof, and overlapped, covered and concealed at its end portions by the outer rand, said strip being engaged 55 with the body layer and outer rand, so that the strip maintains the molded form of the heel base.

2. A heel base as specified by claim 1, the end portions of the stiffening strip being 60 provided with upwardly projecting spurs engaging the outer rand, and its midlength portion with downwardly projecting elongated spurs engaging the body layer and stiffening the strip. 65

3. A heel base as specified by claim 1, the ends of the stiffening strip being narrower than the spaces between the nails which attach the heel base and a heel, so that when 70 the base is incorporated in a shoe, the ends of the strip are located between adjacent nails.

In testimony whereof I have affixed my signature.

CHARLES O. RYBERG.
